(57) CLAIM

I claim the ornamental design for a bottle, as shown and described.

DESCRIPTION

FIG. 1 is a front view of the bottle of the present invention.

FIG. 2 is a rear view of the bottle of FIG. 1.

FIG. 3 is a top view of the bottle of FIG. 1.

FIG. 4 is a bottom view of the bottle of FIG. 1; and,

FIG. 5 is a right side view of the bottle of FIG. 1, the right side view being a mirror image.

1 Claim, 2 Drawing Sheets
